ALARM DEVICE FOR SAFES

Angelo Biasi, Hazleton, Pa.,

Refile for abandoned application Serial No. 113,659, June 4, 1926. This application April 25, 1933, Serial No. 667,770

5 Claims. (Cl. 177—316)

This invention relates to new and useful improvements in an alarm for safes.

The present application is a refile of the original abandoned application, filed by me on June 5, 1926, Serial No. 113,659.

The invention has for an object the construction of a device as mentioned which is characterized by an arrangement whereby an alarm is given when a safe is lifted from the ground without first adjusting certain arrangements to cut off the alarm.

Still further the invention contemplates a further arrangement whereby the alarm is given in the event that the door of the safe is opened without first adjusting the mechanism so as to turn off the alarm.

Another one of the objects of this invention is the provision of a further arrangement whereby the alarm is given in the event that certain drawers in the safe are opened without first setting the alarm system in a certain manner.

As another object of this invention it is proposed to construct the safe with a compartment in which the alarm is arranged and to form the walls of the compartment with a plurality of openings communicating to the exterior.

As another object of this invention, it is proposed to provide an arrangement whereby the openings in the walls of the compartment are normally closed but automatically opened upon the sounding of the alarm.

This invention also contemplates the provision of a pair of switch control handles arranged upon the exterior of the safe and adapted to set in specific relation stationary switches and a pair of adjustable internal switches within the safe so as to control the operation of the alarm.

As another object of this invention, it is proposed to utilize a plurality of rods arranged in a movable manner and normally held, and associated with mechanism to cause the sounding of the alarm when these rods move in predetermined manners.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a perspective view of a safe which is constructed with an alarm device according to this invention.

Fig. 2 is a fragmentary enlarged detailed view of a portion of Fig. 1 illustrating in particular one of the adjustable switch control handles.

Fig. 3 is a transverse vertical sectional view of the safe shown in Fig. 1, this view being as though taken on the line 3—3 of Fig. 4.

Fig. 4 is a fragmentary sectional view as though taken on the line 4—4 of Fig. 3.

Fig. 5 is a fragmentary enlarged detailed view of one of the external switch handles shown in Fig. 1 and some of the interior switches.

Fig. 6 is a sectional view taken on the line 6—6 of Fig. 5.

Fig. 7 is a sectional view taken on the line 7—7 of Fig. 5.

Fig. 8 is a schematic wiring diagram of the device.

Fig. 9 is a fragmentary enlarged detailed view of a portion of Fig. 3.

Fig. 10 is a fragmentary horizontal sectional view as though taken on the line 10—10 of Fig. 9.

Fig. 11 is a detailed view of a portion of Fig. 8 but showing in particular the construction of one of the switches.

Fig. 12 is a horizontal sectional view looking in the direction of the line 12—12 of Fig. 3.

Fig. 13 is a fragmentary sectional view taken on the line 13—13 of Fig. 12.

Fig. 14 is a fragmentary sectional view taken on the line 14—14 of Fig. 13.

The alarm device for safes according to this invention is shown incorporated in a safe 10 having a door 11 hingedly mounted at one side 12 and at the other side provided with a conventional dial combination lock 13. This safe is constructed with a compartment 14 separated from the atmosphere by a wall formed with a plurality of openings 15. An acoustic alarm 16 is mounted in the compartment 14 and is adapted to give an alarm wherein the sound passes through the opening 15 to the exterior. The safe 10 is also provided with several drawers 10^a, other types of drawers 10^b, still further different types of drawers 10^c, etc., as is conventional in safe constructions.

A means is provided for operating the alarm 16 in the event that the safe is lifted from the ground by unauthorized persons who do not properly set the alarm prior to lifting. This means comprises a rod 17 vertically slidable within a compartment 18 formed in the safe and having a

head 19 on its bottom end extendable through an opening 20 in one of the legs of the safe and engaging the ground. A spring 21 acts between the head 19 and a portion of the safe for normally 5 urging the rod 17 downwards. A bracket 22 is attached upon the upper end of the rod 17 and carries the contact 23 engageable with a stationary contact 24 constituting a switch for operating the alarm as hereinafter described in detail.

10 Another arrangement is provided for causing the operation of the alarm when certain drawers of the safe are opened as for example, drawers 10^b. This arrangement comprises levers 25 pivotally mounted intermediately at 26 upon the safe and 15 having their tail ends disposed in the path of motion of the drawers 10^b and their other ends supporting fingers 27 attached upon rods 28 vertically slidably mounted within the compartment 18. As shown on the drawing, there are two adjacent vertical rods 28, each provided with one of the fingers 27 and each of the fingers 27 is supported by one of the ends of the levers 25. The arrangement is such that if one of the drawers 10^b is opened, one of the rods will move downwards under the force of gravity and if the other drawer 10^b is opened then the other rod moves downwards. One of the rods 28 is provided with a bracket 29 at its top carrying a contact 30 engageable with a stationary contact 31 arranged 25 in the alarm circuit as hereinafter fully explained. The other rod 28 is provided with a head piece 32 carrying a contact 33 engageable with a stationary contact 34 also in the alarm circuit as herein-after further explained.

30 An arrangement is also provided for operating the alarm in the event that the external control handles 42 are not set in proper places upon the scales 36. These external control handles are arranged in association with internal switches 35 and switches 38. Each of the internal switches 38 is pivotally supported intermediately at 37 and is engageable with stationary contacts 38' on moon-shaped members 39. The switches 38 are provided with tails 40 which extend into the path 45 of motion of the drawers 10^a in many positions. In other positions of the switches the tails 40 are disposed free from the drawers. The switches 38 must be manually moved. The drawers 10^a may be manually opened and closed only when 50 the switches 38 are in such positions that the tails 40 do not obstruct motions of the drawers. The feature of this arrangement lies in the fact that the drawers cannot be opened except if the switches are set to certain positions.

55 The switches 35 are self closing and mounted behind slots 41 formed in the safe slidably supporting the control handle 42 which have wing shaped inner ends 43 adapted to selectively pry open the switches 35. The switches 35 connect 60 with leads 45 and in series with the contacts in the moon-shaped member 39. The contacts 38', the leads 45 and the switches 35 are arranged in parallel with each other. All of the switches 35 and the leads 45 of one of the switches 38 are ar- 65 ranged in one vertical row to be controlled by one of the control handles 42, and the other switches 35 in the leads 45 connected with the other switch 38 are arranged in another vertical row to be controlled by the other control handles 42.

70 A schematic wiring diagram of the device is illustrated in Fig. 8. The loud speaker 16 is connected in series with a switch 46, a source of power 47 and the switches 35 and 38. A spring 48 normally tends to urge the switch 46 closed. 75 This switch is held open when the safe door 11

is closed by a finger 49 projecting from the safe door 11 and engaging against the switch as schematically shown on the drawings.

The switches 38 are in series with the negative lead of the source of power 47. One of the switches 38 is capable of making contact with anyone of the group of contacts 38' on one of the moon-shaped members 39. The other of the switches 38 is capable of making contact with anyone of the contacts 38' on the other moon-shaped members. Since the two switches 38 may contact with two of the contacts 38', it is pointed out that the switches 38 contact with a pair of contacts 38'. If the switches 35 are so set by the control handles 42 as to open the circuits connecting with said certain pair of contacts, then the alarm will not be sounded in the event that the safe door 11 is opened but, if the switches 35 by the control handles 42 are set at the wrong positions then a complete circuit will exist through the alarm 16 which will necessarily sound when the switch 46 is closed.

If anyone attempts to carry the safe away when it is closed, the alarm circuit will be closed because the contacts 23 and 24 of the mechanism 25 previously described, short circuit the switch 46. When the door of the safe is closed the switch control handles 42 may be moved up and down opening any of the switches 35 without the alarm sounding. When the door of the safe is closed, 30 if any of the drawers 10^b are opened by tilting the safe or cutting out portions of the safe to reach them, the levers 25 will be caused to move so that the contacts 30 and 31 or 33 or 34 engage each other to close the circuit through the alarm. The contacts 23 and 24, 30 and 31, and 33 and 34 are arranged in parallel with each other and shunted across the switch 46. When the safe door is open the drawers 10^a may be readily reached but cannot be opened unless the tails 40 of the switches 38 are moved, for example, to the dot and dash positions illustrated in Fig. 8. It should be understood that the switches 38 are pivoted at 37 and, therefore, when the tail ends 40 are moved the switches 38 will engage different contacts 38'. 45 This will necessitate some adjustment to prevent the alarm from ringing, for example, the switch 46 may be held opened.

In Fig. 11 a detail of one of the switches 38 has been illustrated. It should be noticed that the moon-shaped members 39 are urged against the contact 38, by reason of springs 50 acting between stationary elements 51 and the moon-shaped members. In order that the drawings are not unduly confused only two of the leads 45 have been 55 illustrated but it must be understood that there are more leads 45 as shown in Fig. 8. Each of the leads 45 connect with a contact 38' arranged between the teeth of the serrated moon-shaped member so that the switch contact 38 may selectively engage with any one of the contacts 38'.

An electro-magnet 52 is also arranged in the alarm circuit and has its core connected with cords 53, which connect with the free ends of flat elements 54 hingedly mounted at their other ends 65 upon the inside wall of the compartment 14. These flat elements 54 are provided with top projecting portions 56 which are of the same shape and size and engage into the openings 15 in the normally closed position of the flat element. Out 70 of line with the projections 56, there are openings 57 in each of the flat elements 54 so that sound waves may pass through from the interior compartment 14 to the atmosphere in the event 75

that the flat elements 54 are moved from their closed positions.

Cables 53 pass over guiding pulleys 56 and connect with the free ends of the flat elements 54 so that upon retraction of the core of the solenoid, 5 52, the flat elements 54 are moved to the dot and dash lines, position shown in Fig. 13, in which position communication is established from the interior compartment 14 to the atmosphere. Co- 10 axial springs 58 are mounted upon the pivoted points 55 of the flat members 54 and act between the flat members and the inner wall of the safe for normally urging the flat members into their normal positions. Every time the alarm 16 operates the solenoid 52 will be energized and cause 15 the flat members 54 to move to the opened positions so that the sounds from the alarm may reach the exterior. Normally the flat elements 54 are in closed positions. This prevents dust 20 and dirt from entering the compartment 14 through the opening 15. When the alarm functions, for any reason whatsoever, the flat elements are moved to open positions so that the sounds of the alarm may freely pass to the atmosphere. 25

While I have shown and described the preferred embodiment of my invention, it is to be understood that I do not limit myself to the precise construction herein disclosed and the right is reserved to all changes and modifications coming 30 within the scope of the invention as defined in the appended claims.

Having thus described my invention, what I claim as new, and desire to secure by United 35 States Letters Patent is:—

1. A device of the class described, a safe with a compartment separated from the outside atmosphere by a wall having a plurality of openings connecting the interior with the atmosphere, 40 an acoustic alarm within said compartment, flat elements movably mounted upon the inner side of said wall and having projections engaging into said openings in closed positions for closing the openings and having openings out of line with said projections, means for normally urging said flat elements into closed positions, means for operating said alarm, and means for moving said flat elements from closed positions so that the sound of the alarm may pass through the openings in the flat elements and wall. 50

2. A device of the class described, a safe with a compartment separated from the outside atmosphere by a wall having a plurality of openings connecting the interior with the atmosphere, an 55 acoustic alarm within said compartment, flat elements movably mounted upon the inner side of said wall and having projections engaging into said openings in closed positions for closing the openings and having openings out of line with said projections, means for normally urging said flat elements into closed positions, means for operating said alarm, and means for moving said flat elements from closed positions so that the 60

sound of the alarm may pass through the openings in the flat elements and wall, said flat elements being pivotally mounted at one of their ends, a solenoid in series with said alarm and having a movable core and said means for moving the flat elements including cords connected with the other ends and connected with said movable core. 5

3. A device of the class described, a safe with a compartment separated from the outside atmosphere by a wall having a plurality of openings connecting the interior with the atmosphere, an acoustic alarm within said compartment, flat elements movably mounted upon the inner side of said wall and having projections engaging into said openings in closed positions for closing the openings and having openings out of line with said projections, means for normally urging said flat elements into closed positions, means for operating said alarm, and means for moving said flat elements from closed positions so that the sound of the alarm may pass through the openings in the flat elements and wall, said means for urging said flat elements into closed positions comprising springs acting against the flat elements and the inner wall of said compartment. 10 20 25

4. A device of the class described, a safe with a compartment separated from the outside atmosphere by a wall having a plurality of openings connecting the interior with the atmosphere, 30 an acoustic alarm within said compartment, flat elements movably mounted upon the inner side of said wall and having projections engaging into said openings in closed positions for closing the openings and having openings out of line with said projections, means for normally urging said flat elements into closed positions, means for operating said alarm, and means for moving said flat elements from closed positions so that the sound of the alarm may pass through the openings 35 40 in the flat elements and wall, comprising cables connected with said flat elements, and a solenoid with its movable core connected with said cables.

5. A device of the class described, a safe with a compartment separated from the outside atmosphere by a wall having a plurality of openings connecting the interior with the atmosphere, an acoustic alarm within said compartment, flat elements movably mounted upon the inner side of said wall and having projections engaging into said openings in closed positions for closing the openings and having openings out of line with said projections, means for normally urging said flat elements into closed positions, means for operating said alarm, and means for moving said flat elements from closed positions so that the sound of the alarm may pass through the openings in the flat elements and wall, said flat elements being pivotally mounted to constitute the movable mounting thereof. 45 50 55 60
